UNITED STATES PATENT OFFICE

2,283,968

MOLD

Fredrick H. Bunch, Ottumwa, Iowa

Application April 16, 1941, Serial No. 388,845

1 Claim. (Cl. 25—121)

This invention relates to molds especially adapted for molding cement or plastic building blocks, and has for the primary object the provision of a portable device of the above stated character which may be easily and quickly set up for forming cement into hollow building blocks having the usual grooved ends and may be easily and quickly removed from the formed block without disturbing or otherwise damaging the block and will permit a person to manufacture a large number of such blocks within a comparatively short period of time and at a nominal cost.

With these and other objects in view as will become more apparent as the description proceeds, the invention consists in certain novel features of construction, combination and arrangement of parts which will be hereinafter more fully described and claimed.

For a complete understanding of my invention, reference is to be had to the following description and accompanying drawings, in which—

Figure 1 is a top plan view illustrating a mold constructed in accordance with my invention.

Figure 2 is a side elevation illustrating the device.

Figure 3 is a sectional view taken on the line 3—3 of Figure 1.

Figure 4 is an end elevation illustrating the device.

Figure 5 is a fragmentary perspective view illustrating a portion of the bottom wall and a pair of guide rods thereon.

Figure 6 is a perspective view illustrating one of the side walls.

Referring in detail to the drawings, the numeral 5 indicates the base plate having secured on its top face inwardly of the edges thereof strips to form cleats 6 for assisting in maintaining the walls of the device in proper position upon the base plate.

Rising vertically and integral with the top face of the base plate are spaced tapered posts 7, the purpose of which is to form the usual openings in a cement building block. By having the posts 7 tapered towards their unattached ends will facilitate the removal of the device from the block after the latter has set.

Removably mounted on the base plate 5 within the cleats 6 are side walls 8 and 9 and end walls 10 and 11. The end wall 10 is connected to the side wall 8 by hinges 12. The end wall 10 and side wall 9 are rigidly connected by corner braces 13. Also the end wall 11 is rigidly connected to the side wall 8 by corner braces 14. 55

Secured to the inner faces of the walls heretofore mentioned are liner plates 15 preferably constructed of metal and formed on the liner plates carried by the end walls 10 and 11 are relatively spaced half round ribs 16, the purpose of which is to form the usual end grooves found in a cement building block.

Pairs of guide rods 18 are secured to the base plate 5 and extend through brackets 19 secured on the outer faces of the end walls 10 and 11 to assist in retaining the walls in proper position upon the base plate. The cleats that engage the end walls 10 and 11 are much shorter in length than the cleats that engage the side walls 8 and 9 so that they will not interfere with the guide rods.

The brackets 19 are preferably in the form of elongated tubular sleeves, as clearly shown in Figure 4, extending substantially the full height of the end walls.

A latch 21 is mounted on the side wall 9 and coacts with a keeper 22 secured on the vertical edge of the end wall 11 for detachably connecting the side wall 9 to said end wall 11. The latch is of the pivoted spring influenced type having a thumb piece 23 whereby the latch may be readily moved on its pivot by a pressure placed on the finger piece to disengage the latch from its keeper.

In operation, the various parts are set up, as shown in Figure 1, and the space occurring within the upstanding walls is filled with cement or other plastic material and after said material has set, the entire device is inverted and placed upon a pallet or other similar support. The latch is then disengaged from the keeper and the walls 9 and 10 are swung away from the molded article. With the walls 9 and 10 in the stated position it is a very simple matter to remove the walls 8 and 11 endwise away from the molded article without damaging or disturbing said article.

It is to be understood that when the device is inverted and prior to moving the walls, the base plate is first removed.

A device of the character described and shown in the drawings will permit a person to accurately and rapidly form cement or other plastic material into the shape of a conventional building block. This work, as before stated, can be carried out rapidly and without danger of damaging or injuring the molded block after it has been placed upon a pallet or like support due to the ease and simplicity with which this device may be removed from the molded block.

Further, it will be seen that a device of this

kind can be economically manufactured and will be extremely durable and easily carried from one place to another.

While I have shown and described the preferred embodiment of my invention, it will be understood that minor changes in construction, combination and arrangement of parts may be made without departing from the spirit and scope of the invention as claimed.

Having thus described my invention, what I claim is:

In a mold, a base plate, side and end walls removably mounted on said base plate, cleats on said base plate to engage with said walls for centering of the walls on said base plate, vertical tubular guides carried by certain of said walls and extending throughout the height of the walls, and guide rods carried by the base plate and extending freely into the guides, said rods being coextensive with the guides.

FREDRICK H. BUNCH.
